UNITED STATES PATENT OFFICE

CHESTER A. THOMPSON, OF BARRE, VERMONT, ASSIGNOR TO VERMONT MARBLE COMPANY, OF PROCTOR, VERMONT, A CORPORATION OF VERMONT

DESIGN FOR A MONUMENT

Application filed April 20, 1931. Serial No. 39,576. Term of patent 14 years.

To all whom it may concern:

Be it known that I, CHESTER A. THOMPSON, a citizen of the United States, residing at the city of Barre, in the county of Washington and State of Vermont, have invented a new, original, and ornamental Design for Monuments, of which the following is a specification, reference being had therein to the accompanying drawings.

In the accompanying drawings Fig. 1 is a front view, Fig. 2 a side view and Fig. 3 a back view of my new design for a monument.

I claim:

The ornamental design for a monument, as shown.

In testimony whereof I affix my signature.

CHESTER A. THOMPSON.
